UNITED STATES PATENT OFFICE.

WINSLOW F. SAMPSON, OF GOFFSTOWN, ASSIGNOR, BY DIRECT AND MESNE ASSIGNMENTS, TO THE SAMPSON AUTOMATIC HEEL BURNISHING MACHINE COMPANY, OF MANCHESTER, NEW HAMPSHIRE.

HEEL-BURNISHING MACHINE.

SPECIFICATION forming part of Letters Patent No. 444,388, dated January 6, 1891.

Application filed March 24, 1890. Serial No. 345,178. (No model.)

To all whom it may concern:

Be it known that I, WINSLOW F. SAMPSON, a citizen of the United States of America, and a resident of the town of Goffstown, in the county of Hillsborough and State of New Hampshire, have invented certain new and useful Improvements in Heel-Burnishing Machines, of which the following is a full, clear, and exact description.

- 10 The improvements of this invention are particularly adapted to heel-burnishing machines, such as described in my application for Letters Patent of the United States, Serial No. 320,524.
- 15 The improvements, in substance, consist, first, of a jack for securing a boot or shoe with its heel edge exposed and the inner surface of its sole against a rest therefor at one end of a reciprocatingly-rotated or otherwise suitably-operated shaft, composed of a toggle-lever, which by one of its arms is jointed on said shaft and has a rest for the treading-face of the heel that is opposite to the heel-rest of said shaft, and is swiveled on the toggle-lever at the joint of its arms, in combination with a spring which is held on said shaft and at rest and pressing on the toggle-lever at the outer side of its joint and also preferably with a handle, which is hinged to the arm of the toggle-lever opposite to that jointed to said shaft, and is adapted to be swung inward toward the shaft and there held against accidental movement and outward from the shaft and to be brought to an abutment on the toggle-lever and all otherwise in its outer position to serve as a handle through which to operate the toggle-lever, and thereby to place its swiveled rest against or to remove it from contact with the treading-face of the heel, in the first instance fastening and holding the boot or shoe by its heel on the shaft, and in the second instance releasing it for its removal and the placing and holding of another; second, of an arm or frame carrying
- 25 the burnisher, which is constructed and arranged and operated to move the burnisher over the edge of the boot or shoe, suitably located in the machine therefor, and from the treading-face of the heel to the upper, and

vice versa, and to secure elastic pressure of 50 the burnisher on the edge of the heel in its movement, as aforesaid, and which is transversely vertically divided in a parallel line with that of the heel into two parts, connected together by a swivel-joint, and otherwise 55 adapted the part carrying the burnisher to swing on the other part, in one direction against and in the other direction by the tension of a spring suitably applied to the two parts therefor; third, of mechanism composed, 60 in substance, of a horizontal shaft adapted to be rocked to and fro in suitable stationary bearings, a vertical ratchet-wheel and concentric gear-wheel held on it, and both adapted to rotate as one on said rocker-shaft, a vertical arm, which is fulcrumed and thus is adapted to swing on said shaft, and which carries a pawl that in one direction of the swing of the arm and against the tension of a spring engages and thereby turns said ratchet and 65 gear-wheel, and in the other direction of the swing of the arm and by the reaction of said spring passes freely over and without effect on said ratchet-wheel, an arm held on said rocker-shaft and in one direction of the rock 70 of the shaft to abut against and thereby to swing said arm-carrying pawl in a direction to secure, by its pawl, a rotation of said ratchet and gear-wheel on said shaft, in combination 75 with mechanism which is constructed and arranged and is in suitable connection with said rotating gear-wheel, and a frame or arm carrying a burnisher to move said burnisher forward and backward across the edge of a heel suitably presented and held to it and 80 from the treading-face of the heel to the upper of the boot or shoe; fourth, of a horizontal rocker-shaft held on suitable stationary bearings, arms which are fixed and radially project in opposite directions from said shaft, 85 and each at its outer end is provided with an abutment, both projected toward each other, in combination with a frame or arm, which is suitably supported and carries a burnisher held on it, and has a pulley-wheel for rotating the burnisher, two driving-pulley wheels held and each capable of separate and independent rotation on said arm or 95

frame, a belt to drive said driving-pulley wheels and the burnisher, and a belt-shipper device which is held on and is arranged to be moved on said burnisher-carrying frame and has a block presenting two abutment-faces, one on opposite sides thereof and both in the vertical plane of and between said abutments of said rocker-shaft and to be worked first by one and then by the other of said shaft-abutments, and thereby to secure a movement of said belt-shipper in opposite directions on said burnisher-carrying frame or arm, and a placing of said driving-belt in operative position on either one or the other of said pulley-wheels, driven in opposite directions and a rotation of the burnisher in either one or the other direction, as the case may be.

In addition to the above, the invention consists of other improvements in detail hereinabove described, and pointed out in the claims.

In the drawings forming a part of this specification, a machine for burnishing the heels of boots or shoes and of the class to which the improvements of this invention are particularly applicable is illustrated.

Figure 1 is a plan view. Fig. 2 is a front elevation. Figs. 2^a and 2^b are sectional views in detail, as will hereinafter appear. Fig. 3 is an end elevation of the left-hand side of the machine. Fig. 4 is a plan view in detail and enlarged of the mechanism or jack (turned over) to secure a boot or shoe in position in the machine for burnishing its heel. Fig. 5 is a side elevation in detail and enlarged of the jack mechanism in its proper position. Fig. 6 is a vertical sectional view in detail and enlarged, line 6 6, Fig. 1. Fig. 7 is a plan view in detail, enlarged, and detached of the under side of the frame which carries the burnisher-tool, all as hereinafter appears. Fig. 8 is an elevation of a part of the mechanism of Fig. 7, and detached therefrom.

In the drawings, A represents the horizontal bed of the machine, supported on legs A¹⁹ at each corner, two partially shown, or in any other suitable manner.

B is the driving-shaft. This shaft is horizontal, and it is under the rear portion, and it is supported and turns in suitable fixed depending bearing-blocks A² A² of the bed A.

B' B² are fixed and loose pulley-wheels held on the shaft B at its end projecting beyond the right hand of the bed, and B³ is a vertical pinion gear-wheel fixed on the projecting end portion of the shaft which is opposite to the pulley B'. The pinion B³ is at the rear and meshes a vertical gear-wheel B⁴, held and turning on a fixed horizontal stud B⁵ of the block A²⁰ at the left hand of the bed. The gear-wheel B⁴ has a radial slot B⁶, at which, by headed screw-bolt and screw-nut B⁷, pivot-connection is made of one end of a pitman-rod B⁸, which at its other end is pivoted and connected to the lower end of a vertical arm B⁹, intermediately fulcrumed and hung on a fixed horizontal stud A³ of a post A⁴ at the front

side and left hand of the bed, and at its upper end portion it has a segmental gear B¹⁰, concentric with the axis of stud A³.

C is a vertical pinion gear-wheel at upper side of and meshing segmental gear B¹⁰ and held on the left-hand end portion of a horizontal shaft C², that turns in bearings of the upper end of a post A¹ and extends therefrom, and its end portion C³ at the right hand of the bed A is enlarged and presents an end and vertical flat face C⁴ in a plane crossing the axial line of the shaft C² and on this face C⁴ the boot or shoe (not shown) the heel of which is to be burnished is secured by a jack mechanism, hereinafter described, and which constitutes one feature of this invention. The axis of shaft C² is in the vertical plane of the axis of fulcrum-stud A³ and pivotal connection of lever-arm B⁹ and pitman-rod B⁸ when said arm and rod are in the position shown in Fig. 1.

All parts of the jack mechanism are carried by and they rotate in common with the shaft C², and the mechanism consists of an arm C⁸, a toggle-lever C⁹ C¹⁰, a bent spring C¹¹, and, preferably, a handle C¹² for the toggle-lever for convenience of working it to place the jack out of its holding position against the treading-face of the boot or shoe, otherwise at the inner side of the sole at its heel portion at rest against the heel-face C⁴ of the shaft C², upon and over which the boot or shoe is entered. The several parts referred to are in a common horizontal plane below the shaft C², and the arm C⁸ is rigidly but adjustably held on and projects angularly from and toward the heel-holding face C⁴ of said shaft, and at its outer end it is pivoted or hinged to the outer end of one arm C⁹ of the toggle-lever C⁹ C¹⁰, the pintle-joint C¹³ of which is in a vertical plane forward of the heel-face C⁴ of the shaft C², and its arm C¹⁰ at its outer end is in front of the shaft C². The pintle of the pintle-joint C¹³ of the toggle-lever extends upward and into a position opposite to the heel-face C⁴ of the shaft C², where it has a flat face C¹⁴ to bear on the treading-face of the heel of a boot or shoe, otherwise entered onto the shaft and resting at the inner heel portion of the sole against the heel-face of said shaft C², all as described. The bent spring C¹¹ is made of a strip of heavy sheet metal. This spring at one end is rigidly held on and extends from the rear side of the shaft C² in a curvilinear direction around the outside of both arms of the toggle-lever, and its outer free end rests upon the toggle-lever joint C¹³, all so as to exert pressure on the toggle-lever and with its arms straightened out to press thereon and there-through, and thus to firmly confine a heel to and upon the heel-face C⁴ of the shaft C².

The handle C¹² for the toggle-lever is hung by a butt-hinge C¹⁵ on the outer end of the arm C¹⁰ of the toggle-lever, so as to be swung and placed either inward toward the shaft C² or outward and in extension of said arm C¹⁰ of the toggle-lever and placed inward. It is

conveniently stowed away, as it were, and there retained against accidental displacement by a bent spring C¹⁶, attached to arm C¹⁰ and arranged to bear on the butt-hinge of the handle and placed outward against the end of the toggle-arm C¹⁰. It serves as a rest against which the operator can press his leg, and thereby work the toggle-lever in a direction against its bent spring C¹¹ to release the jack 5 from its hold on and confinement of the boot or shoe at its heel against the heel-face C⁴ of the shaft C² when desired to remove the boot or shoe and replace it with another.

The boot or shoe jacked as explained has 15 the edge of its heel which is to be burnished exposed at all parts and from one end of the breast of the heel to the other thereof and from the treading-face of the heel to the upper of the boot or shoe.

20 Again, the boot or shoe jacked, as described, is reciprocated in a circle about the axis of the shaft C² by the action of the driving-shaft B, pitman-rod B⁸, arm B⁹, and its segmental gear B¹⁰ and pinion-gear C on the shaft C², it 25 being understood that the driving-shaft is under continuous rotation. By adjusting the pivot-connection of pitman-rod B⁸ with the driving gear-wheel B⁴ at a greater or less distance from the center of rotation of said 30 wheel, the length of the arc of reciprocation of boot or shoe heel can be made more or less, as may be required or desired, to suit heels of greater or less length of edge to be burnished.

35 C¹⁷ is an arc-shaped shield held on the post A⁴ and in position to cover and guard the pinion and segmental gear-wheels C B¹⁰ at and around their upper portions.

D² is a horizontal shaft carrying the burnisher D. (Shown in dotted lines, Fig. 1.) The burnisher D is of circular shape with a convex or rounded edge, and is confined on and between collars D¹⁰ at one end portion of the shaft, and all so that the burnisher-wheel 40 is in the vertical plane of the heel of the boot or shoe jacked on the shaft C², and the axis of the burnisher-shaft D² is in a vertical plane coincident with that of said shaft C², and the shaft D² extends toward the right hand of the 45 machine. The burnisher-shaft at its opposite end portions turns in bearings D³ of one end of a frame or arm D⁴ D¹¹, which is in two transverse sections or parts butted end to end and jointed by a swivel-pin D¹², and also 50 arranged and applied together, as hereinafter explained, and the part D⁴ at its end opposite to that swiveled to part D¹¹ is of fork shape, and is fastened to a horizontal bar or rod D⁶, suspended at its opposite end portions and extending across and between and free to be moved, as hereinafter appears, lengthwise, and to rotate in bearings at the upper ends of upright forked arms A⁵ of a fixed post A⁷ at the rear portion of the machine-bed A. The vertical plane of the axis 55 of the rod D⁶ is parallel to the vertical plane of that of the shaft C², having the boot or

shoe jacked to it, as stated, and also of that of the shaft D², carrying the burnisher D.

The burnisher D in operation is at the upper side of the boot or shoe heel, jacked and reciprocated as described. The carrier or frame D⁴ D¹¹ for the burnisher D, with the burnisher out of operative position, inclines more or less upward from its end hung on the rod D⁶.

M is a lever which extends more or less horizontally from front to rear, and at the front of the machine has a handle M², at the rear a counterbalancing-weight M³, and intermediate of its ends it is hung on a fulcrum M⁴ of the post A⁷, supporting, as explained, the burnisher-carrier D⁴ D¹¹.

M⁵ is a vertical spiral spring, at its lower end hung on the handle-lever M and at its upper end on the front swiveled part D¹¹ of the burnisher-carrier D⁴ D¹¹, and by pressing this lever downward said carrier is lowered and the burnisher is placed in operative position on the heel edge of the jacked boot or shoe, and is there held (see Fig. 2^a) by means of side pin M⁶ at the front end portion of the handle-lever M, then in engagement with a hook-shaped end M⁷ of a vertical arm M⁸, rigidly held on one end of a horizontal rod M⁹, which is contained and turns in a horizontal tubular bearing M¹⁰, secured to the bed A, Fig. 2^b, and at its opposite end has a rigidly-attached and upwardly-projecting arm M¹¹, on which is hung one end of a spiral spring M¹², that at its opposite end is hung on a stationary post M¹³, and all so that the tension of the spiral spring M¹², working on the arm M¹¹ and thence through the shaft M⁹ and its catch-hook M⁷, holds said catch in engagement with the pin M⁶ of the handle-lever M until otherwise it is released of engagement in the operation of the machine, as will hereinafter appear. The spiral spring M⁵ allows the burnisher to yield upwardly and downwardly, so that the burnisher can conform to the varying distances of the heel edge from the axis of its oscillating rotation; and again as the part D¹¹ of the burnisher-carrier D⁴ D¹¹, and to which said spring M⁵ is hung and on which it acts, is swiveled on the part D⁴, as described, the burnisher can further automatically adjust itself to the heel edge, for the reason that the burnisher is thus made capable of a rocking movement on the heel-edge, secured from the tension of said spring, limited, however, in an upward direction by an adjustable stop-pin M¹⁴, held on the part D⁴ and bearing on the upper face of the part D¹¹ of the burnisher-carrier and at the side of the axis of the swivel-connection of said parts opposite to that at which said spring is hung.

M¹⁵ is an upright rod, which is secured to the handle-lever M, preferably, so as to be vertically adjustable thereon, and extends upward toward and against the under side of the part D⁴ of the burnisher-carrier D⁴ D¹¹, and downward loosely through and below the

bed A, where it is provided with a stop-block M¹⁶, preferably adjustable on it. This rod M¹⁵ moves up and down with the handle-lever M, and in the operation of the machine its upper end limits the downward movement of the burnisher-carrier D⁴ D¹¹, as also of the burnisher in relation to the heel edge being burnished, and its stop-block M¹⁶ by abutment against the under side of the bed A limits the upward movement of the handle-lever M, and also the burnisher-carrier D⁴ D¹¹, when the holding-catch M⁷ M⁸ is freed from the pin M⁶ of the handle-lever, as will hereinafter appear and be explained in the operation of the machine.

M¹⁶ M¹⁷ is a vertical bell-crank lever, which is fulcrumed at its angle M¹⁸ on a fixed support M¹⁹ of the bed-plate A and so that its upper arm M¹⁶ lies across the vertical plane of movement of the handle-lever M and its lower arm M¹⁷, having a slotted guide M²⁰ for the passage of the driving-belt, (not shown,) is at one side of the fixed and loose pulley-wheels B' B² of the driving-shaft.

The crank-lever M¹⁶ M¹⁷ and the slotted guide M²⁰ constitute a shipper to ship the driving-belt from the loose to the fixed pulley, and vice versa.

Forcing the handle-lever M downward to place the burnisher into operative position on the edge of the heel of the jacked boot or shoe and to engage it with the catch-arm M⁷ therefor, all as described, brings that lever into abutment against the upper edge of the upper arm of the crank-lever and swings the crank-lever on its fulcrum in a direction to move the driving-belt engaged with, as stated, from off the loose pulley onto the fixed pulley, and thereby the machine is put into operation.

Freeing the handle-lever and allowing it to move upward by the action of its spring M⁵, all as described, releases the crank-lever M¹⁶ M¹⁷ to the reaction of a spiral spring M²¹, at one end secured to the lower arm M¹⁷ of the crank-lever and at the other end to the fixed support M¹⁹, whereby the crank-lever is moved in a direction carrying the driving-belt from off the fixed pulley onto the loose pulley securing a stopping of the running of the machine.

F is a vertical pulley-wheel held on and located between the opposite end bearings of the burnisher-shaft D², which is thereby or otherwise suitably confined against lengthwise movement through its bearings D³. F² F³ are two similar pulley-wheels arranged side by side and each carrying, respectively, a similar and smaller pulley-wheel F⁴ F⁵. These pulley-wheels are severally arranged to turn in pairs on the rod D⁶; but each pair F² F⁴ and F³ F⁵ turns independently and separately from the other pair and all confined against endwise movement on said rod by the fork ends D⁵ of the burnisher-carrying frame D⁴ D¹¹, or otherwise suitably. Each smaller pulley-wheel F⁴ F⁵ of the two pairs of pulley-wheels is connected by a belt, (not

shewn,) so as to be driven in opposite directions, and the larger pulley-wheels F² F³ have a belt F⁶, Fig. 3, to connect them, either one or the other, according as the belt is placed on one or the other, with the pulley-wheel F of the burnisher-shaft D², and thereby to rotate the burnisher in one direction when the belt F⁶ is on the pulley-wheel F² and in the other and opposite direction when said belt is on the other pulley-wheel F³, and the belt is automatically shifted from one pulley-wheel F² to the other F³, and vice versa, as will hereinafter appear.

The rod D⁶, having the burnisher-carrying frame D⁴ D¹¹ held on it, as explained, extends from its said supports A⁵ toward the left of the bed, and its outer end portion D⁷ is screw-threaded and receives a screw-threaded and milled collar G, adjustable lengthwise on said rod. This collar G has a peripheral groove G³ at opposite horizontal diametrical points engaged by the upper fork-shaped ends of a vertical lever-arm G⁴, hung on a fixed horizontal fulcrum-pin A⁹ of an upright A¹⁰ and carrying a vertical bevel gear-wheel G¹⁴. The bevel gear-wheel G¹⁴ engages a larger vertical bevel gear-wheel H, integral with or attached to and turning as one with a vertical ratchet-wheel J⁸ on a horizontal shaft H², supported and turning at its opposite end portions in suitable bearings of the post M³ and the upward extension of the bearing-block A²⁰, hereinbefore referred to, of the bed A.

J⁷ is a gravity-pawl located at the upper side and by its toe engaging the teeth of the ratchet-wheel J⁸ and by its heel fulcrumed on the upper end of a vertical arm J⁶, hung and swinging on and projecting downward below the shaft H² and at its lower end portion presenting a flat and vertical face J⁹, that is on the same side of it as the engagement of the pawl J⁷ with the ratchet-wheel J⁸.

J¹⁰ is a spiral spring at one end hung on the upper end portion of the pawl-carrying arm J⁶ and at the other end on the upright A¹⁰, before referred to, of the bed. By a swing of the arm J⁶ in one direction and the then engagement of the pawl with the ratchet-wheel J⁸ the ratchet-wheel J⁸ and its companion bevel gear-wheel H are turned in a corresponding direction, and on a swing of the arm J⁶ in the opposite direction the pawl moves backward over the ratchet-wheel without effect thereon to turn it. The swing of the arm J⁶ to turn the ratchet-wheel, as described, is against the tension and its swing in the opposite direction is by the reaction of the spring J¹⁰.

J¹¹ is an arm fixed on the shaft H² and having a side friction-roller projection J¹² at its outer and lower end for abutment against the flat face J⁹ of the pawl-carrying arm J⁶, and also that by rotating the shaft H² in the proper direction to place the projection J¹² of its arm J¹¹ in abutment with the flat face J⁹ of said arm J⁶ the ratchet-wheel J⁸ and its companion bevel gear-wheel H are turned, as

above explained, and thereby the bevel gear-wheel G^{14} , in mesh with said gear-wheel H and its shaft G^7 , are also turned, causing, through the crank connection of fork-shaped lever G^4 with said shaft G^7 and grooved collar G of rod D^6 , a lengthwise movement of said rod D^6 forward and backward through the bearings of its support, and also of the arm or frame $D^4 D^{11}$ and of the burnisher, across the edge and from the treading-face of the heel toward the upper of the boot or shoe, and vice versa.

The above-described movement of the shaft H^2 is a rocking one, and the movement described of the ratchet-wheel J^8 and its companion bevel gear-wheel H and the bevel gear-wheel G^{14} and its shaft G^7 are severally an intermittent rotary one, but always in one and the same direction.

The rocking movement of the shaft H^2 , as above stated, is secured from the connection of the crank-arm H^{10} of the shaft through the pitman-rod H^4 with the vertical arm B^9 for vibrating the edge of the heel of the jacked boot or shoe under and in contact with the burnisher, and said arm B^9 is vibrated by the rotation of the gear-wheel B^4 in connection with it by pitman-rod B^8 .

O is a collar fixed on the end portion of the shaft H^2 opposite to that having the crank-arm H^{10} , and $O^2 O^3$ are two (more or less) radial arms held on and projecting in opposite directions from the collar O and having a more or less V -opening between them. Each radial arm $O^2 O^3$ carries an adjustable, but otherwise stationary, abutment-block O^4 , projecting toward each other and within the V -opening of the arms. The abutment-blocks O^4 are in a common vertical plane, and that of an abutment-block O^5 for both of them, and which is held on the lower end portion of a vertical rod O^6 , preferably adjustably fixed in one end of a horizontal lever-arm O^7 , that is fulcrumed on and lies across the under side of the part D^4 of the burnisher-carrying frame $D^4 D^{11}$, and has a horizontal segmental gear O^8 in mesh with a horizontal segmental gear O^9 of a vertical shaft O^{10} , turning and suitably confined in bearings of and also projected upward and downward from the part D^4 of said frame $D^4 D^{11}$, and at each of its opposite end portions provided with an arm O^{11} , each of which has an eye-guide O^{12} , which are otherwise arranged to engage the upper and lower lengths of the driving-belt F^6 , connecting loose pulley-wheels $F^2 F^3$ of the rod or shaft D^6 , reciprocated as before described, with the pulley-wheel F of the burnisher D . By the rock of the shaft H^2 , as described, said abutment-blocks $O^2 O^3$, held on the shaft, as explained, are brought, the one in the one direction of the rock of the shaft and the other in the other direction of the rock of the shaft into bearing and action on the abutment-block O^5 , making part of the mechanism engaged with the driving-belt F^6 , as described, and thereby through the operation of said

mechanism the belt is shifted from one to the other of the pulley-wheels $F^2 F^3$, and thereby the direction of rotation of the burnisher is changed, it being understood, and, as before stated, that these pulley-wheels through their smaller pulley-wheels and suitable belt-connections are driven in opposite directions.

The machine composed of parts severally and all constructed and arranged as described in use and its driving-shaft B put into operative connection through the driving-belt with the driving-power employed is first provided with a boot or shoe by securing it at its heel to the headed end C^3 of the shaft, as explained, on which by depressing the handle-lever M the burnisher D is brought to bear and held at a bearing on the exposed edge of the jacked heel, and the driving-belt is shipped onto the fixed driving-pulley wheel B^3 of the driving-shaft, thus putting the machine into and continuing it in operation until by the rotation of the ratchet-wheel J^8 , the pin M^{22} thereof being brought to a bearing on the vertical arm M^{11} , connected to the catch-lever M^7 , holding the handle-lever M in its depressed position, said catch is released from said lever, on which and by the upward movement of said lever the driving-belt is shipped from the fixed driving-pulley to the loose pulley of the shaft, which secures a stop of the running of the machine, as also a lifting of the burnisher from the heel edge it had been burnishing, freeing the boot or shoe for removal from the machine by releasing the hold of the jack thereon, as explained, and placing the machine in readiness for another boot or shoe to be inserted and jacked or secured and set into motion, all as above described.

With the machine in operation, as explained, the jacked boot or shoe is vibrated forward and backward with its heel edge in contact with the burnisher, which at the same time is rotated in one and then in an opposite direction, is moved across the edge of the heel from the treading-face thereof to the upper of the boot or shoe, and vice versa, and, further, is exerting an elastic or yielding pressure on and is adjusting itself inward to and outward from and otherwise, owing to the two-part construction of its carrying-frame $D^4 D^{11}$, and swivel-connection of said parts to the varying curves and outlines of the heel edge. The movement of the burnisher over and across the edge of the heel from the treading-face of the heel to the upper and the change in the direction of rotation of the burnisher and the stopping of the running of the machine are severally and all primarily secured by the rock of a single shaft H^2 , which of itself is adapted and carries mechanism in part fixed to and in another part turning on it and all otherwise in combination with mechanisms interposed between the parts carried by and the parts turning on it, and the devices to be operated thereby as to secure the said several operations specified.

For the better illustration and description

of this invention, all as above, it was thought advisable to illustrate and describe many parts in no manner belonging to the present invention, but to that forming the subject-matter of the application referred to, and all such parts are hereby separately and severally disclaimed, except in so far as they are in their combinations with the new elements of the machine of this invention distinct subject-matters of invention, all as fully appears in the several clauses of claims hereof.

Having thus described my invention, what I claim and desire to secure by Letters Patent, is—

15 1. In a machine for burnishing the edges of heels of boots or shoes, in combination, a shaft suitably supported and adapted to be reciprocatingly rotated and at one end to secure the rest of a boot or shoe at its inner heel portion, the combination of a jack composed of a toggle-lever jointed by one of its arms to said shaft and having the joint of its arms opposite to said end rest of said shaft for the heel, a rest held and swiveled on it and presenting a face toward the heel-face of said shaft, and a spring held on said shaft and arranged to press against and on the outer side of and against the joint of said toggle-lever, a burnisher, and means to operate said burnisher and to move it across the edge and from the treading-face to the sole face of the heel held between the heel-rests of said jack and said reciprocatingly-rotated shaft carrying said jack, all substantially as described, 35 for the purpose specified.

2. In a machine for burnishing the edges of heels of boots or shoes, in combination, a shaft suitably supported and adapted to be reciprocatingly rotated and at one end to secure the rest of a boot or shoe at its inner heel portion, the combination of a jack composed of a toggle-lever jointed by one of its arms to said shaft and having the joint of its arms opposite to said end rest of said shaft for the heel, a rest held and swiveled on it and presenting a face toward the heel-face of said shaft, a spring held on said shaft and arranged to press against and on the outer side of and against the joint of said toggle-lever, and a handle to the outer end of the arm of the toggle-lever opposite to that arm jointed to said shaft and adapted otherwise to be swung toward and outward from said shaft into line and butted against the end of the arm to which it is jointed, a burnisher, and means to operate said burnisher and to move it across the edge and from the treading-face to the sole-face of the heel held between the heel-rests of said jack and said reciprocatingly-rotated shaft carrying said jack, all substantially as described, for the purposes specified.

3. In a machine for burnishing the edges of heels of boots or shoes, the combination, with the frame or arm D⁴ D¹¹, which is made in two parts connected together by a swivel-joint D¹² and has its part D⁴ at its outer end suspended for the frame to be moved later-

ally and horizontally and to swing vertically, and its part D¹¹ at its outer end provided with the burnisher, of a spring applied to the part D¹¹ of said frame and otherwise adapted to exert yielding pressure thereon in its swivel movement, and an abutment M¹¹, held on the part D⁴ and adapted for contact with the part D¹¹, substantially as described, for the purposes specified.

4. In a machine for burnishing the edges of heels of boots or shoes, substantially as described, a horizontal rocker-shaft H², having suitable bearings, means to rock said shaft, a ratchet-wheel J⁸ and a gear-wheel H¹, held thereon and adapted to rotate as one, a vertical arm J⁶, fulcrumed and to swing on said shaft and at its upper end having a pawl J⁷ to engage the ratchet-wheel, and thereby to rotate it and its said gear-wheel in one direction of the swing of the vertical arm and in the other direction thereof to pass freely over the ratchet, a radial arm held on and in one direction only of the rock of said shaft to work on said pawl-carrying arm, and a spring at one end held on said arm and at the other on a fixed support, in combination with mechanism connected with the burnisher of the machine and with and to be operated by the rotation of said gear-wheel H¹, whereby the burnisher is made to travel to and fro over the edge and from the treading-face of the heel to the upper, and vice versa, substantially as described, for the purpose specified.

5. In a machine for burnishing the edges of heels of boots or shoes, in combination, appliances for holding the boot or shoe with the edge of its heel exposed, means for reciprocatingly rotating said boot or shoe holding appliances, a burnisher, means for rotating said burnisher, consisting of a pulley-wheel held on said burnisher and together turning in suitable bearings, two loose pulley-wheels held and turning and located side by side on a common shaft and separately adapted to be driven, and a belt connecting said loose pulley-wheels and said burnisher pulley-wheel, a horizontal rocker-shaft H², having suitable bearings, means to rock said shaft H², arms O² O³, held on and radially projected from said shaft H² and both in a common vertical plane and each at its outer end having an abutment-block O⁴, an abutment-block O⁵, having an abutment-face on its opposite sides and in the vertical plane of the abutment-blocks O⁴ of said shaft H² and adapted to swing to and fro on a suitable support, a belt-shipper device in suitable connection with said driving-belt for the burnisher and adapted to rotate on a suitable support, and means connecting said belt-shipper and said swinging abutment-block and adapted to rotate the former from the swing of the latter, substantially as described, for the purposes specified.

6. In a machine for burnishing the edges of heels of boots or shoes, substantially as described, a horizontal rocker-shaft H², turning in suitable bearings, a pin M²², eccentric-

ally held on said shaft, a lever-catch $M^7 M^8$, arranged to be rocked on a suitable support in one direction by said pin and against and in the opposite direction with a spring M^{12} , applied to said catch, and a lever M , adapted and arranged for said lever-catch $M^7 M^8$ to be engaged and disengaged from it, in combination with an arm or frame $D^4 D^{11}$, at one end swinging on a suitable horizontal support and at its other end carrying the burnisher, a vertical spring M^5 , at one end hung on said carrier and at the other end on said lever, and

a vertical rod M^{15} , carried by said lever and adapted at its opposite ends to act as a stop to the up-and-down swing of said frame, substantially as described, for the purpose specified. 15

In testimony whereof I have hereunto set my hand in the presence of two subscribing witnesses.

WINSLOW F. SAMPSON.
